UNITED STATES PATENT OFFICE.

IVAN RODIONOVITCH AFONIN, OF LONDON, ENGLAND.

OIL-STORAGE TANK.

Application filed July 25, 1927, Serial No. 208,359, and in Great Britain July 6, 1927.

This invention relates to means for preventing the evaporation of crude oil and oil products in storage tanks, the means being of the type in which the surface of the liquid is covered with separate floating cells.

According to the present invention the cells are so constructed that the circumferential cells are always forced into close contact with the walls of the tank, irrespective of any expansion or contraction or deformation of shape due to changes of temperature or to other causes.

According to the invention, each cell is substantially in the shape of a parallelopipedon, but as shown in Fig. 1 of the accompanying drawings, opposite sides which are partially immersed in the liquid, are inclined so that the cell tends to rotate about two axes at right angles to each other, passing the centre of figure when the cell is partly immersed in the liquid. Fig. 2 shows a vertical section of the tank and the arrangement of a series of the cells.

The sides A', A² of each cell in the row are inclined from left to right, the side A' of one cell resting on and fitting closely in engagement with the side A² of the next adjoining cell. C represents the level of the liquid in the tank.

The side A' tends to slide downward and the side A² to rise. These movements tend to press the end cells of the row into contact with the wall D of the tank and consequently to maintain a tight closure which prevents evaporation of the liquid in spite of changes in the dimensions of the tank.

If, for instance, a gap tends to form between the cell 1 and the wall D, the cell 1 slides downwards and outwards and thereby moves the cell 2 in the opposite directions, the side A² rising and the side A' descending. As the side A' descends, a larger portion of the weight of that part of the cell is supported by the liquid; there is, consequently, less pressure on the surface A² of the adjoining cell 3, which is raised and at the same time experiences a thrust to the left and in this manner the movement of the cells is transmitted across the row to the terminal cell 4.

The surface of the terminal cells of any row in contact with the wall is preferably rounded as shown in order to prevent their

movements from being hindered by the presence of rivets or other obstructions.

55

The cells are attached together by chains E or other means which allow relative motion between them.

The explanation of the action of the sides A', A² of each cell apply, also, to the corresponding action exerted on the sides B', B².

When it is not necessary that the liquid must be protected against the heat of the sun, the cells could be made open at the top.

65

Having thus described the nature of my said invention and the best means I know of carrying the same into practical effect, I claim:—

1. Means for preventing the evaporation of crude oil and oil products in storage chambers, said means comprising a plurality of separate floating cells which cover the surface of the liquid, most of such cells being substantially in the form of a parallelopipedon and the contacting sides of adjacent cells being similarly inclined to the vertical.

75

2. Means for preventing the evaporation of crude oil and oil products in storage chambers, said means comprising a plurality of separate floating cells which cover the surface of the liquid, most of such cells being substantially in the form of a parallelopipedon, one inclined side of one cell resting upon and fitting closely in engagement with an inclined side of an adjoining cell.

85

3. Means for preventing the evaporation of crude oil and oil products in storage chambers, said means comprising a plurality of separate floating cells which cover the surface of the liquid, most of such cells being substantially in the form of a parallelopipedon, the surface of a terminal cell of any series in contact with a wall of the tank being rounded.

90

4. Means for preventing the evaporation of crude oil and oil products in storage chambers, said means comprising a plurality of separate floating cells which cover the surface of the liquid, most of such cells being substantially in the form of a parallelopipedon, and means securing adjacent cells together and permitting relative movement between the cells.

100

5. Means for preventing the evaporation

105

of crude oil and oil products in storage chambers, said means comprising a plurality of separate floating cells which cover the surface of the liquid, most of such cells being substantially in the form of a parallelopipedon, and chains securing adjacent cells together.

6. A cover for an oil storage tank com-

prising separate flexibly connected floating cells, the abutting sides of adjacent cells being inclined in opposite directions to the vertical and in sliding contact with one another.

In testimony whereof I have signed my name to this specification.

IVAN RODIONOVITCH AFONIN.
